UNITED STATES PATENT OFFICE.

NICHOLAS HERMANN STENECK, OF HOBOKEN, NEW JERSEY.

LIQUID-MEASURING AND REGISTERING DEVICE.

1,264,218.

Specification of Letters Patent.

Patented Apr. 30, 1918.

Application filed August 11, 1915. Serial No. 45,028.

To all whom it may concern:

Be it known that I, NICHOLAS HERMANN STENECK, a citizen of the United States, and residing at Hoboken, in the county of Hudson and State of New Jersey, have invented 5 certain new and useful Improvements in Liquid-Measuring and Registering Devices, of which the following is a clear and concise specification, reference being had to the 10 accompanying drawings, forming a part of this specification.

This invention relates to registering devices.

One object of the invention is to provide 15 a liquid measuring and registering device, being comparatively simple of construction and to be readily attached to a liquid holding tank.

Another object of the invention resides 20 in the provision of means to register automatically the quantity of liquid deposited from time to time in the vessel to which the device is attached.

A still further object of the present invention resides in the provision of means to prevent 25 the device from registering at times other than when filling the tank or container.

It is still further designed to provide a 30 liquid measuring and registering device which is readily and efficient to use and dependable at all times and which is not operable through any other means except through the introduction of liquid into the 35 vessel, tank or container to which the device is attached.

It is still further designed to provide a 40 liquid measuring and registering device in which the registering means are prevented from operation through possible outside influences.

With the above and other objects in view, the invention consists in the construction and novel combination of parts, hereinafter 45 fully described, illustrated in the accompanying drawing, and pointed out in the claims appended hereto, it being understood, that various changes in the form, proportion, size, arrangement and minor details of 50 construction, may be resorted to without departing from the spirit or sacrificing any of the advantages of the invention.

In the drawings:

Figure 1 is a sectional view through a 55 liquid containing vessel, as for instance an automobile gasoline tank or the like and

the liquid measuring and registering device attached thereto.

Fig. 2 is a sectional view along the line 60 A—A of Fig. 1.

Fig. 3 is a top view of the filler vent cap.

Fig. 4 is a sectional view through the filler 65 vent and cap, showing more precisely the method of operating the valve mechanism.

Fig. 5 is a sectional view through the valve 70 chamber and connecting nipple, showing more clearly the path of the liquid and the operation of the valve and brake, and

Fig. 6 is a sectional view along the line 75 B—B of Fig. 5.

Referring now more particularly to the drawings, character 7 indicates a liquid containing tank, such as is used on motor vehicles and the like and provided with a filling vent 8 being threaded to engage with the thread 75 of a cap 9, to securely close said vent.

Secured to one side of the tank 7 in any convenient manner, preferably through means of flanged bushing 10, is the measuring and recording chamber 11, being of any desired 80 form or shape, preferably cylindrical and provided with a nipple 12, threaded so as to engage the thread of the bushing 10.

Measuring and registering chamber 11 is 85 provided at the center of its upper and lower covers with suitable bearings 13 and 14 to receive a spirally grooved or threaded shaft 15. The spiral groove or thread of the shaft being of varying pitch determined by the shape of tank 7, that is for 90 tanks whose vertical sections are not rectangular, the pitch is such that the rotation of the shaft is in direct proportion to the volume as indicated by the level of the liquid in the tank 7. A gear 16 is keyed to 95 one end of the aforesaid shaft 15, engaging the pinion 17, which latter is provided at the upper end with ratchet teeth, normally held in engagement with corresponding teeth on the actuating shaft 18 of a suitable 100 register 19, by means of spring 20.

Movably mounted on the grooved shaft 15 is a float 21, carrying a suitable element adapted to engage the thread or groove of shaft 15, so that when said float is raised by 105 the increasing height of the liquid, it will rotate the shaft 15, since the float itself is restrained from rotation.

The gear 16 being keyed to the aforesaid shaft 15 and normally in mesh with pinion 110 17, will when rotated through the pinion 17 actuate the register 19.

In order to prevent the possibility of registering at any other time than when refilling the tank, the registering chamber 11 is provided with a valve. In order to guide the valve stem 23 and disk 22, a member 24 threaded to engage similar threads on the nipple 12 is provided. The bearing support 27 of member 24 is provided with holes 25 to permit the flow of liquid to the valve chamber 26.

The aforesaid bearing support 27 serving also as a seat for the valve spring 28. One end of the valve stem 23 terminates in a fork 29, adapted to engage the shaft 15 and prevent its rotation when the valve is closed. The opposite end of the valve stem 23 is provided with a disk 30 forming a contact surface for the nose of the lever 31 and also as a retainer for the valve spring 28.

The valve operating lever 31 is pivoted to the supporting member 32 through means of a pin or the like 33. This supporting member 32 consists preferably of a cylindrical body portion provided with a thread engaging the external thread of member 24 and arms 32', 32'', so arranged that the disk 30 can pass freely through the bight of said arms.

The pin 34 is provided to limit the upward movement of the valve lever 31. A rod 35 terminating in a fork 36 at its lower end is slidably held in a bearing 37 at its upper end. Rim 38 on cap 9 is provided for the purpose of depressing rod 35 and also sealing the bearing 37 so as to prevent possible leakage of the liquid contained in the tank 7.

Reference to the aforesaid drawings clearly indicate, that removal of the cap 9 uncovers vent 8 and bearing 37, permitting rod 35 to move upward, since spring 28 bearing on disk 39 imparts a pressure on the nose of the lever 31 and thereby pressing said lever upward and in turn the rod 35 to a position such as is permitted by the stop pin 34. In this position of the mechanism more clearly indicated by Fig. 5, the valve stem 23 having been moved laterally by the expansion of spring 28, disengaging the spiral threaded or grooved shaft 15 and the fork 29 and opening the valve; the flow of liquid is then permitted into the measuring and registering chamber 11 in which it will reach a level predetermined by the level in tank 7.

The vertically guided float 21 when moving downward with the liquid in the chamber 11 causes a rotation of the shaft 15 in such a direction as to disengage the ratchet from pinion 17 and shaft 18, thus preventing the rotation of shaft 18; when moving upward the float 21 causes the shaft 15 to rotate in such a direction, that the gear 16 in mesh with pinion 17 permits the normal engagement of the ratchet teeth of pinion 17

and shaft 18 due to the spring 20 and consequently rotates shaft 18 and register 19.

The liquid deposited in the tank 7 through vent 8 raises the level in tank 7 and the passage of liquid through holes 25 of the valve 70 and into the measuring and registering chamber 11 causes an equal rise in said chamber 11.

Since the rising level in the tank causes the float 21 to rise also the actual rise of 75 liquid is faithfully recorded on the register dial and thereby registering the true volume of liquid deposited in tank 7.

Having thus described my invention what I claim as new and desire to have protected 80 by Letters Patent is:

1. In a device of the character described, a tank provided with a vent, a closure for the vent, a float chamber provided with a float and a register and communicating with the tank and also provided with an operating shaft for the register, said shaft having connection with said float, a valved communication between the tank and float chamber, and means for governing the operation of 90 the valve and also for governing the operation of said shaft upon the opening and closing of the vent closure so as to operate the register.

2. In a device of the class described, a 95 tank provided with a vent, a closure for said vent, a float chamber communicating with the tank by means of a passage and provided with a register, and means operated by the opening or closing of the vent closure for 100 opening or closing said passage and also governing the operation of the register.

3. In a device of the class described, a tank provided with a vent, a closure for the vent, a float chamber having communication 105 with the tank and provided with a register, a float in the float chamber, an operating shaft for the register having operative connection with said float, a rod located in the communication between the tank and the 110 float chamber and terminating in a fork, a valve on said rod adapted to open and close said communication between the tank and the float chamber, a spring on said rod for normally holding said fork or said rod away 115 from said operating shaft and to maintain said valve in open position, and means controlled by the closing of the vent closure for moving said valve to close the communication between the tank and float chamber and 120 move said fork of said rod into engagement with said operating shaft and thereby prevent operation of said operating shaft.

4. In a device of the class described, a tank provided with a vent, a closure for said 125 vent, a float chamber having communication with said tank and provided with a register, and in which chamber is located an operating shaft to operate the register, a rod located in the communication between the tank 130

and float chamber and at one end terminating in a fork, a float in the float chamber having operative connection with said operating shaft, a valve on said rod to open and close the communication between the tank and float chamber, a spring on said rod for normally holding said valve in a position to permit communication between the tank and chamber and to hold said forked end of said rod out of engagement with said operating shaft, a lever mounted in said tank and engaging said rod, a rod mounted in the tank and having connection with said lever, and means on the vent closure for engaging the second mentioned rod upon the closing of 15 the vent closure to actuate said lever and said forked rod to move the valve with the latter and thereby close the communication between the tank and chamber and cause the fork of said forked rod to engage the register operating shaft and prevent operation of the latter. 20

In testimony whereof I affix my signature in the presence of two witnesses.

NICHOLAS HERMANN STENECK.
